(57) **CLAIM**

The ornamental design for a digital notebook, as shown and described.

DESCRIPTION

FIG. 1 is a rear perspective view of a digital notebook, showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an enlarged detail view of a portion of the digital notebook shown in area 8 in FIG. 1.

The broken lines in the drawings illustrate portions of the digital notebook that form no part of the claimed design. The dash-dot-dash broken lines encircling portions of the digital notebook in FIG. 1 and illustrated in an enlarged view in FIG. 8 form no part of the claimed design.

1 Claim, 8 Drawing Sheets
